DUAL KEY LOCK STRUCTURE

Clifford H. Wasson, Indianapolis, Ind., assignor to The Nik-O-Lok Company, Indianapolis, Ind., a corporation

Application August 30, 1954, Serial No. 452,870

7 Claims. (Cl. 70—63)

This invention relates to a dual key lock structure. In recent years there has been a marked trend away from the original grocery store custom of delivering merchandise to the home of the purchaser. Several factors have been responsible. Two of the most important of these are the likelihood of damage to the merchandise during transit, and the possibility of theft of some of the packages or of some of their contents. As a consequence, supermarkets, grocery stores and the like today almost universally fail to make home deliveries.

With the thought in mind of eliminating these disadvantages in order to revive the original home delivery custom and thereby stimulate business by rendering greater service, the present invention has been conceived and perfected. To this end, the merchandise purchased by a shopper is placed within a protective wire or other suitable basket having affixed thereto the dual key lock structure which is the subject of this application. The cashier of the store will, after putting all purchased merchandise within the basket, place a cover thereupon and lock it in position. This will be done through the use of a master key which is always retained by the clerk. The master key will actuate the lock in just one manner, i. e. by causing the latch bolt to move into extended, locking position relative to the cover or top of the basket. At such time, the key which will unlock the bolt, i. e. the second key, is taken out of its keyway, where it is retained against removal so long as the bolt is in retracted position, and handed to the customer. Thus the only key which will make possible a removal of the cover is in the possession of the purchaser. Once the delivery boy arrives at her home she can insert the key given to her by the cashier, unlatch the bolt, take off the cover and remove the contents from the basket. Upon turning the latch bolt to retracted position the key will once again have been rotated to a position where it cannot be removed until the master key is again inserted by the cashier for the next customer. The delivery boy, of course, returns to the store with the basket and cover.

It is the primary object of the present invention to provide a lock structure capable of operation in the above sequence for the accomplishment of the foregoing objectives.

It is a further object of the present invention to provide a dual key lock construction that has a minimum number of parts and is operated in an easy, facile manner.

The full nature of the invention will be understood from the accompanying drawings and the following description and claims:

In the drawings, Fig. 1 is a section view of the basket in which the groceries are placed and to which the lock construction is connected.

Fig. 2 is a top plan view of the lock construction.

Fig. 3 is a front elevation view of the lock construction with keys removed and with parts broken away.

Fig. 4 is a back elevation view of the construction with the back cover plate removed, showing the latching bolt in retracted or unlocked position.

2

Fig. 5 is a view similar to Fig. 4, with the exception that the latch bolt is shown in locked, extended position.

Fig. 6 is a perspective view of one of the two keys that is used to operate the construction.

Fig. 7 is a perspective view of the other of the two keys.

In the drawings the basket into which the housewife or shopper may place the merchandise she is purchasing is shown generally at 10, it comprising the wire frame 11 and the cover 12. It is to be understood, of course, that any suitable basket of proper shape and proportions may be employed.

The lock mechanism which comprises the invention per se is shown generally at 13 and includes a housing 14 having a pair of transverse bores 15 and 16 formed therethrough. Rotatably disposed within the bores are plugs 17 and 18. Each plug has a keyway 19 formed therein, the keyway lying between the peripheral surface of the stem 20 and the adjacent face 21 of the plug. Each stem 20 is connected to one of the discs 22 and 22a. Each disc and the front shoulder portions 23 of the plugs are slightly larger in diameter than the inside diameter of the bores, thus preventing any axial movement within the bore. The discs are each suitably connected as by screws 24 to a plug and are, therefore, rotatable therewith.

A stub shaft 25 is connected to the disc 22a and is rotatable therewith. Extending radially from this shaft is the pin 26. Enveloping the shaft is a lever arm 27 having an apertured end portion 28. As will be observed in Fig. 4, this apertured portion fits around the shaft and includes an enlarged extension or cut-out quadrant 29 in which the pin is received. A cap 30 is frictionally clamped over the shaft and bears down upon the adjacent portion of the lever arm 27 thereby holding it against axial movement on the shaft.

A hook 31 is formed on the lever arm, it being connected by the spring 32 to the pin 33 fixed to the housing. The spring normally biases the opposite or operating end of the lever into engagement with the stop 34, and into engagement with one or the other of the plug stops 35 or 36. These last two stops, as shown in Figs. 4 and 5, are in the form of buttons or pins connected to disc 22 and are in spaced arcuate relation adjacent its periphery.

Affixed to disc 22 (which as previously mentioned is secured to one of the plugs) is the pin 37 to which is connected the spring 38. The opposite end of this spring is attached to pin 39 fixed to the housing. The spring will normally bias disc 22 and plug 18 to the position shown in Fig. 5 wherein the latch bolt 40 is in extended or locked position. The latch bolt, as will be observed, is pivotally connected at 41 to disc 22 and is movable therewith. A stop pin is provided at 42 so that as the latch bolt is moved to extended position it will be jutting straight out in the manner shown in Fig. 5.

The keys which will operate the lock construction are shown in Figs. 6 and 7 wherein key 43 is shown having two blades and key 44, three blades. Any desired number of blades may be employed, these being formed in a manner well known in the pin-tumbler art, it having previously been pointed out herein that the locks are of pin-tumbler character. As is conventional in this art a plurality of bores 45 and 46 is provided. In each bore there are positioned the conventional tumbler pins 45a and tumbler spring 45b as shown in Fig. 3. When the key is in its keyway and bores 45 are in alignment with bores 46, the pins and springs in the respective bores will be moved by the key to a position such that the plug may be rotated. That is to say, the pins within the respective bores are held by the key blade with their meeting ends flush with the meeting surfaces of the plug and housing.

As will be observed in Figs. 2 and 3, when the bolt is in latched or locking position the key 44, which is the cus-

omer's key, will be capable of being removed or inserted since bores 45 and 46 are in alignment. When, however, the latch bolt is moved as hereinafter set forth in detail, to retracted or unlocked position (see Fig. 4) the bores will not be in alignment and the key cannot be removed. With this construction and arrangement, the customer's key will always be retained within the keyway until such a time as the cover is latched in place upon the merchandise basket whereupon that key can be removed and placed in the customer's custody until the delivery of the basket to her home. At such time she uses the key to unlatch the bolt whereupon the plug will once again have been rotated to a position where the key cannot be removed.

Once the master or cashier's key 43 is placed within the plug 18 that plug may be rotated relative to the housing. As it is thus rotated, pin 26 which is normally located midway between the ends of cutout quadrant 29 will be rotated with the plug without in any way imparting movement to the lever arm 27 until such a time as the pin has traversed the extension or cut-out quadrant and engaged the shoulder 47. At that point further movement of the plug and pin will cause the lever arm to be pivoted against the bias of spring 32 from the position shown in full lines in Fig. 4 to the position shown in dotted lines therein.

With the lever arm moved away from stop 35, the disc 22 will immediately be biased by spring 38 from the position shown in Fig. 4 to the position shown in Fig. 5. This rotation or bias is, of course, not permitted so long as the lever arm is in engagement with the stop 35. Once, however, the arm is pivoted, as aforesaid, there no longer is any restraint against the action of spring 38 whereupon, as stated, plug 18 will be rotated until the latch bolt connected thereto is in the extended position shown in Fig. 5.

At this time the lever arm will have been biased by spring 32 into engagement with stop 36 thereby preventing further clockwise rotation of the plug relative to Figs. 4 and 5. It is at this point that the bores 45 and 46 are in alignment and the key may be removed from the keyway and given to the customer for use at the time the groceries arrive at her home. Upon inserting the key she can rotate the plug 17 in a counterclockwise position as viewed in Figs. 4 and 5. As the plug is thus rotated, stop 35 will move the adjacent lever arm downwardly or away from it against the bias of spring 32 until pin 35 has passed the end of the lever arm whereupon spring 32 will once again bias that arm back to the position shown in full lines in Fig. 4. Once again it is impossible to turn plug 17 or to remove the customer's key therefrom until the master or cashier's key is placed within plug 18.

As is apparent in Fig. 1, the latch bolt will extend up into a recess formed in the cover 12 and will hold the cover in locked position upon the basket until the foregoing procedure is followed.

While the invention has been illustrated and described in detail in the drawings and foregoing description, the same is to be considered as illustrative and not restrictive in character, it being understood that only the preferred embodiment has been shown and described and that all changes and modifications that come within the spirit of the invention and the scope of the claims are also desired to be protected.

The invention claimed is:

1. A dual key lock structure comprising a housing having a pair of openings, a key receiving plug in each opening, said plugs and said housing having a plurality of alignable bores extending radially thereof, tumbler pins disposed in said bores and normally locking said plugs against rotation, the pins yielding to a key of proper form inserted in each of said plugs to permit plug rotation, one of said plugs having a latch bolt pivotally connected thereto and being rotatable between a first position wherein said bolt is extended and the alignable bores in the housing and said one plug are in alignment and a second

position wherein said bolt is retracted and said last mentioned bores are out of alignment, means connected to said one plug normally biasing it to said first position, an element connected to said other plug normally biased into engagement with said one plug for retaining it in said first or second positions selectively, and means effective upon key rotation of said other plug to move said element out of engagement with said one plug.

2. A dual key lock structure comprising a housing having a pair of openings, a key receiving plug in each opening, said plugs and said housing having a plurality of alignable bores extending radially thereof, tumbler pins disposed in said bores and normally locking said plugs against rotation, the pins yielding to a key of proper form inserted in said plugs to permit plug rotation, one of said plugs having a latch bolt pivotally connected thereto and being rotatable between a first position wherein said bolt is extended and the alignable bores in the housing and said one plug are in alignment and a second position wherein said bolt is retracted and said last mentioned bores are out of alignment, resilient means connected to said one plug and normally biasing it from said second position to said first position, a pair of abutments connected to said one plug, an element connected to said other plug and normally biased into the path of rotation of one or the other of said abutments for retaining said one plug in said first or second positions selectively, and means associated with said other plug and effective upon its rotation to move said element out of the path of rotation of said abutments.

3. A dual key lock structure comprising a housing having a pair of openings, a key receiving plug in each opening, said plugs and said housing having a plurality of alignable bores extending radially thereof, tumbler pins disposed in said bores and normally locking said plugs against rotation, said pins yielding to a key of proper form inserted in said plugs to permit plug rotation, one of said plugs having a latch bolt pivotally connected thereto and being rotatable between a first position wherein said bolt is extended and the alignable bores in the housing and said one plug are in alignment and a second position wherein said bolt is retracted and said last mentioned bores are out of alignment, resilient means connected to said one plug and normally biasing it from said second position to said first position, an element connected to said other plug, resilient means normally biasing said element into engagement with said one plug, said one plug having a pair of abutments engageable by said element selectively to retain said one plug in either said first position or said second position, said one plug being normally rotatable from said first position to said second position whereby said element is disengaged from the adjacent abutment, and means associated with said element effective upon key rotation of said other plug to move said element out of engagement with said one plug.

4. A dual key lock structure comprising a housing having a pair of openings, a key receiving plug in each opening, said plugs and said housing having a plurality of alignable bores extending radially thereof, tumbler pins disposed in said bores and normally locking said plugs against rotation, the pins yielding to a key of proper form inserted in said plugs to permit plug rotation, one of said plugs having a latch bolt pivotally connected thereto and being rotatable between a first position wherein said bolt is extended and the alignable bores in the housing and said one plug are in alignment and a second position wherein said bolt is retracted and said last mentioned bores are out of alignment, means connected to said one plug normally biasing it from said second position to said first position, an element having a cut-out quadrant formed therein, said element being connected to said other plug and normally biased into engagement with said one plug for retaining it in said first or second position selectively, and lost motion means effective upon key rotation of said other plug to move said element out of engagement with said one plug.

gagement with said one plug, said lost motion means including a pin rotatable with said other plug and disposed within said cut-out quadrant.

5. A dual key lock structure comprising a housing having a pair of openings, a key receiving plug in each opening, said plugs and said housing having a plurality of alignable bores extending radially thereof, tumbler pins disposed in said bores and normally locking said plugs against rotation, said pins yielding to a key of proper form inserted in said plugs to permit plug rotation, one of said plugs having a latch bolt pivotally connected thereto and being rotatable between a first position wherein said bolt is extended and the alignable bores in the housing and said one plug are in alignment and a second position wherein said bolt is retracted and said last mentioned bores are out of alignment, resilient means connected to said one plug and normally biasing it from said second position to said first position, an element having a cutout quadrant formed therein and connected to said other plug, resilient means normally biasing said element into engagement with said one plug, said one plug having a pair of abutments engageable by said element selectively to retain said one plug in either said first position or said second position, said one plug being manually rotatable from said first position to said second position whereby said element is disengaged from the adjacent abutment, and lost motion means associated with said element effective upon key rotation of said other plug to move said element out of engagement with said one plug whereby said one plug is biased by said first mentioned resilient means to said first position, said lost motion means including a stub shaft secured to said other plug axially thereof and having a pin projecting radially therefrom, said pin being disposed within said cut-out quadrant.

6. The combination of an article receiving receptacle having a cover provided with means for receiving a latch bolt and a dual key lock structure secured to said receptacle, said structure comprising a housing having a pair of openings, a key receiving plug in each opening, said plugs and said housing having a plurality of alignable bores extending radially thereof, tumbler pins disposed in said bores and normally locking said plugs against rotation, the pins yielding to a key of proper form inserted in said plugs to permit plug rotation, one of said plugs having a latch bolt pivotally connected thereto and being 40 rotatable from a first position wherein said bolt is extended into locking engagement with the means of said cover and the alignable bores in the housing and said

one plug are in alignment to a second position wherein said bolt is retracted from within said cover means and said last mentioned bores are out of alignment, means connected to said one plug normally biasing it to said first position, an element connected to said other plug normally biased into engagement with said one plug for retaining it in said first or second positions selectively, and means effective upon key rotation of said other plug to move said element out of engagement with said one plug.

10 7. The combination of an article receiving receptacle having a cover provided with latch bolt receiving means and a dual key lock structure secured to said receptacle, said structure comprising a housing having a pair of openings, a key receiving plug in each opening, said plugs and said housing having a plurality of alignable bores extending radially thereof, tumbler pins disposed in said bores and normally locking said plugs against rotation, the pins yielding to a key of proper form inserted in said plugs to permit plug rotation, one of said plugs having a latch bolt pivotally connected thereto and being rotatable between a first position wherein said bolt is extended into locking position within said cover means and the housing and bores of said one plug are in alignment and a second position wherein said bolt is retracted to permit cover removal and said last mentioned bores are out of alignment, resilient means connected to said one plug and normally biasing it from said second position to said first position, a pair of abutments connected to said one plug, an element connected to said other plug and normally biased into engagement with and in the path of rotation of one or the other of said abutments for retaining said one plug in said first or second positions selectively, and lost motion means associated with said other plug and effective upon its rotation to move said element out of engagement with and the path of rotation of said abutments whereby said one plug is biased by its resilient means to said first position.
